DESIGN FOR A FLUORESCENT LIGHTING FIXTURE

Carl X. Meyer, St. Louis, Mo., assignor to Day-Brite Lighting, Inc., St. Louis, Mo., a corporation of Missouri

Application June 18, 1949, Serial No. 3,387

Term of patent 14 years

(Cl. D48—23)

To all whom it may concern:

Be it known that I, Carl X. Meyer, a citizen of the United States and a resident of the city of St. Louis, and State of Missouri, have invented a new, original, and ornamental Design for Fluorescent Lighting Fixture, of which the following is a specification, reference being had to the accompanying drawing, forming part thereof.

Fig. 1 is a bottom perspective view of a fluorescent lighting fixture, showing my new design.

Fig. 2 is an elevational view of the side opposite that shown in Fig. 1; and

Fig. 3 is an enlarged elevational view of the end opposite that shown in Fig. 1; and

Fig. 4 is an enlarged vertical cross-sectional view on the line 4—4 in Fig. 1.

I claim:

The ornamental design for a fluorescent lighting fixture, substantially as shown.

CARL X. MEYER.
